TAPE MEASURE CASE

Andrew J. Banas, Sr., 2647 23rd Ave.,
San Francisco, Calif. 94116

Filed Feb. 18, 1975, Ser. No. 550,889

Term of patent 14 years

Int. Cl. D10—04

U.S. Cl. D10—72

FIG. 1.

FIG. 2.

FIG. 3.

FIG. 4.

FIG. 5.

FIG. 1 is a front and right side perspective view of a tape measure case showing my new design;

FIG. 2 is a top plan view thereof;

FIG. 3 is a front elevational view thereof, the rear being identical thereto with the bracket slot omitted;

FIG. 4 is a right side elevational view thereof, the left side being identical thereto with the bracket slot omitted;

FIG. 5 is a bottom plan view thereof.

I claim:

The ornamental design for a tape measure case, as shown and described.
